(57) CLAIM

The ornamental design for a patio heater, as shown and described.

DESCRIPTION

FIG. 1 is a front, right and top perspective view of a patio heater showing our new design;

FIG. 2 is a rear, left and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view taken from circle 9 in FIG. 1;

FIG. 10 is a partial enlarged view taken from circle 10 in FIG. 2;

FIG. 11 is a partial enlarged view taken from circle 11 in FIG. 2;

FIG. 12 is a partial enlarged view taken from rectangle 12 in FIG. 3; and,

FIG. 13 is a partial enlarged view taken from rectangle 13 in FIG. 4.

The dash-dash broken lines in the drawings depict the portions of the patio heater that form no part of the claimed design.

The dot-dash broken lines in the drawings depict the boundaries of the partial enlarged views that form no part of the claimed design.

1 Claim, 13 Drawing Sheets
